UNITED STATES PATENT OFFICE.

HENRY L. GERKEN, OF NEW YORK, N. Y.

ENGINE CONTROL.

1,233,865.

Specification of Letters Patent. Patented July 17, 1917.

Application filed November 17, 1916. Serial No. 131,833.

To all whom it may concern:

Be it known that I, HENRY L. GERKEN, a citizen of the United States, and a resident of the city of New York, borough of Manhattan, in the county and State of New York, have invented a new and Improved Engine Control, of which the following is a full, clear, and exact description.

My invention relates to means for controlling internal-combustion engines, and it has reference more particularly to means for simultaneously controlling the ignition and the fuel supply of an internal-combustion engine.

15 An object of the invention is to provide a simple and inexpensive control which can be applied to any internal-combustion engine having a carbureter and timer.

Another object of the invention is to provide a control of the class described in which the fuel delivery opening is varied inversely of advance ignition.

I attain the above and other objects of my invention by the structure conventionally disclosed in the accompanying drawings, wherein similar characters of reference indicate corresponding parts in all the views.

Figure 1 is a perspective view of an engine provided with a control embodying my invention;

Fig. 2 is a longitudinal section through the needle valve of a carbureter which is to be operated in unison with the timer of the engine; and

35 Fig. 3 is a diagrammatic view showing that the advance of ignition causes a decrease of fuel supply opening.

Referring to the drawings, 4 is the spark lever which is connected by a rod 5 to a 40 crank 6 mounted to participate in the movement of the lever. The crank is connected by a rod 7 to the timer 8.

The carbureter 9 of the engine has the needle valve 10 thereof threaded in a sleeve 45 11 which is in turn threaded into the body 12 of the carbureter. The sleeve has an arm 13 which may be connected to the rod 5 to be operated when the timer is operated, or it may be connected, as shown in the drawings, 50 by a rod 14 to a bell-crank lever 15 which is connected in turn by a link 16 to the timer 8. It will be seen that the connection between the needle valve and the timer is such that an advance in sparking will cause the

needle valve 10 to descend with the sleeve 55 and reduce the opening supplying fuel to the engine. Inversely, a retard in sparking will increase the opening which supplies fuel to the engine.

While I have described the principle of 60 operation, together with the device which I now consider to be the best embodiment thereof, I desire to have it understood that the device shown is merely illustrative and that such changes may be made as are within 65 the scope of the appended claims.

I claim:

1. An engine control of the class described comprising in combination a carbureter, a spark control, and means connecting the 70 spark control to the carbureter to increase the fuel supply without varying the air supply when the spark is retarded, and vice versa.

2. An engine control of the class described 75 comprising in combination a spark control, a carbureter having a needle valve, and means connecting the needle valve to the spark control to reduce the fuel supply as distinguished from fuel mixture supply 80 when the spark is advanced and increase the fuel supply opening when the spark is retarded.

3. An engine control of the class described 85 comprising in combination a carbureter having a needle valve, a timer for regulating the spark of the engine, and means for operating the timer and the needle valve simultaneously so that an advance in sparking causes a reduction of fuel supply opening, 90 and vice versa.

4. An engine control of the class described 95 comprising in combination a carbureter having a needle valve, a timer for controlling the spark of the engine, and means connecting the needle valve to the timer so that advance of sparking causes a closing of the valve, and vice versa.

5. An engine control of the class described 100 comprising in combination a carbureter having a needle valve, a sleeve threaded into the carbureter and in threaded engagement with the needle valve, a timer, means for operating the timer, and means connecting the timer to the sleeve so that an advance in spark 105 causes a closing of the needle valve, and vice versa.

HENRY L. GERKEN.
